UNITED STATES PATENT OFFICE.

WILLIAM E. WINE, OF TOLEDO, OHIO.

CAR VENTILATOR.

Application filed October 9, 1925. Serial No. 61,485.

My invention relates to new and useful improvements in ventilators for freight cars and has for an object to provide a ventilator, which will be relatively light in weight, strong in construction, efficient in service and easily and readily operated.

Still another object of the invention is to provide a car ventilator which may be quickly and readily installed in the sides or ends 10 of a car, the ventilator consisting simply of a metal frame, a pair of plates having vents or louvers therein, and a divided or hinged door, and means for holding the door open or closed.

Still another object of the invention is to provide a ventilator having plates with louvers formed therein and to provide a door 20 formed of two hinged plates or shutters, and to provide an operating shaft having a pivot- ed link at its one end and an arm at its other, so that when the door is raised, the two plates of the door will swing at an angle to each other and the operating shaft and link and its 30 arm form a support to thereby hold the door tightly and securely in its open position.

With these and other objects in view, the invention consists in certain new and novel arrangements and combination of parts as will be hereinafter more fully described and 30 pointed out in the claims.

Referring to the drawings showing a preferred embodiment of the invention,

Fig. 1 is a vertical central sectional view of my ventilator, the dotted lines showing 35 the door swung to its open supported position.

Fig. 2 is a front view of my ventilator showing the door in its closed position.

Fig. 3 is a vertical sectional view taken 40 on line 3—3 of Fig. 2, looking in the direction of the arrows.

Fig. 4 is a similar view taken on line 4—4 of Fig. 2, looking in the direction of the arrows.

Fig. 5 is a front view with the door removed, the upper portion of the view showing the arrangement of the front louver plate, a portion of this plate being broken away to show the rear louver plate, and 45

Fig. 6 is a fragmentary view of the lower portion of the ventilator with the door 50 swung to its open position.

Referring now more specifically to the several views, there is shown the rectangular ventilator frame 1, the bottom rail 2 being bent downwardly as at 3, to protect the

wooden portion 4 which may be the side or end sheathing of the car.

As may be seen in the several figures, there is provided an inner peripheral rim 5 60 on which is formed at convenient locations, the bosses 6 to which in turn are secured the louver plates 7 and 8, this form of construction rigidly fastening the plates to the frame and presenting substantially a unitary structure.

In Fig. 1 there is shown the plate 7 provided with a plurality of vents or louvers 11, which may be stamped in the plate by subjecting the same to a large press, say 70 a hundred ton press, with suitable dies, these louvers 11 being pressed rearwardly and open at their top as at 12.

The rear plate 8 is likewise provided with louvers 13, these louvers, however, being open 75 at their bottom 14 and so spaced that the opening of the one louver will be above the louver of the cooperating plate; so that any air passing through the louver in the one plate will be directed upwardly and pass 80 through the louver located at the rear and above it.

This prevents any water or snow from being driven in through the openings in the two plates which is the common practice, 85 and shown in a number of my patents and pending applications.

As far as the specification has proceeded, it will be seen that I have provided a frame, 90 preferably of cast steel with convenient arrangements for securing two relatively thin metal plates thereto, each of the plates being provided with oppositely extending and oppositely positioned louvers, so that the air may pass therethrough, but rain, snow and 95 sleet may not enter.

To supply means for closing the louvers as a whole or for permitting the air to pass through them to ventilate the car, I have shown a very simple, but very satisfactory, 100 and efficient arrangement comprising a door 15, which in turn is formed of what might be called, two shutter plates 16 and 17, which are hinged to each other as at 18, the door as a whole being hinged as at 19 to an upper 105 rail 20 integral with the frame 1, as may be seen in Figs. 1 and 2.

Referring for the moment again to the frame 1, it will be remembered that there is provided within the same, the rectangular 110 flange or rim 5, so that the two plates or shutters 16 and 17 of the door, which in turn

are provided with the inwardly extending edges or rims 22 and 23 respectively will encase this inner peripheral rim 5 to thereby provide a relatively tight fit for the door 15 or shutter plates for the louver plates, and at the same time prevent any lateral movement of the door when the same is in its closed position.

It might be well to point out at this time that the upper shutter plate 16 fits up behind the said rail 20 as may be seen in Fig. 1, so that this strip acts as a weather-guard for the upper edge of the door. It might also be pointed out here that the lower shutter 17 of the door is provided with the outwardly extending flange or rim 24 at its upper edge as may be seen in dotted lines in Fig. 1, so that when the two shutters of the door as a whole are in their closed positions, the rim 24 will fit over the bottom rim 25 of the shutter 16. In other words, the two shutters have an interlocking action at their pivotal or hinged point to seal the two shutters about their adjacent edges when the shutter plates are in their closed position.

Now, for holding the door, comprising the two shutter plates, in its closed position, and also for holding the door in its open hinged position, I have provided, what I term, an operating shaft 26 which is held near its opposite ends by the bearing straps 27, the operating shaft being offset near both ends as at 28, its one end 29 (at the left of Fig. 2) fitting within the outer end of a link 30, which link in turn is pivoted as at 31 to the side of the frame 1.

Directly on the opposite side of the frame, I provide a boss 32 which is slotted as at 33, the length of this slot being substantially the length of the link 30. The remaining end of the operating shaft 26, after being offset as at 28, extends upwardly to form the arm 34, and then extends outwardly as at 35 fitting within the slot 33. As the pivotal points 31 and 35 are opposite each other, when the two plates of the shutter are in their closed position, or the door as a whole is closed, the above described arrangement will tightly hold the door in its closed position, thereby preventing any ventilation through the louver plates.

The arrangement above mentioned will also rigidly support the door in its open or broken position. To break the shutter, or in other words, open the door, it is only necessary to grasp the operating shaft 26, and force the same outwardly and upwardly, which in turn, will cause the end 35 of the arm 34 to descend within the slot 33, thus forcing the plates 16 and 17 to pivot and swing the two plates to the positions shown in Fig. 1 in dotted lines. It will be noticed that the link 30 and the arm 34 form braces to rigidly support the divided door in the position shown, the operating bar 26 of

course assuming the position as shown in the dotted lines in Fig. 1, and the full lines in Fig. 6.

In other words, the link and the arm 34 form two legs extending in the opposite directions, both of which are connected with or form a part of the operating shaft 26.

It will be understood without explanation that to close the door as a whole the operating shaft may be grasped and pulled outwardly and downwardly, which in turn will close the shutter plates and tightly hold them in such position.

From the foregoing it will be seen that I have provided a ventilator of relatively simple construction, wherein the frame is arranged to support two louver plates and also to support a door formed of two hinged shutter plates, which, when closed, will tightly encase the said louver plates. At the same time, I have provided means for quickly and easily opening the door and comprising an operating shaft which cooperated at its one end with a slot and at its opposite end with a link, the pivotal points of the slot and link being opposite, so that the door may be held tightly in its closed position, or whereby a rotating of the offset operating shaft will change the pivotal points to thereby securely hold the door in its broken or open position until the operating shaft is again rotated.

Also, it will be appreciated that the pivotal shutter plates act as a further shield even when in their open position for the louver plates to prevent the ingress of any driving snow or rain.

The ventilator is one which is relatively simple to manufacture, easily assembled and will withstand the hard usage incident to the application and usage in a freight car.

Many slight changes might be made without in any way departing from the spirit and scope of the invention.

Having thus described the invention, what I claim as new and desire to secure by Letters Patent is:—

1. A ventilator comprising a frame, plates secured to the frame and having vents therein, an inner peripheral flange, a door formed of two shutter plates hingedly connected to the frame and the two shutter plates having their adjacent edges pivotally secured, the edges of said door fitting about said inner peripheral flange when the door is closed, means for holding the door in its closed position and for supporting the door in its open position; and the two shutter plates of the door extending in angular relation to each other when the door is supported in its open position.

2. A ventilator comprising a frame, louver plates within the frame, a door comprising two sections hinged to each other

and the said door pivoted to the upper portion of the frame, the said door being capable of being swung upwardly and outwardly to thereby angularly position the
5 two sections to thereby allow the air to pass through the louvers and said sections protecting the louvers from the ingress of water when the said door is in its open position and means for holding the two sections
10 in their angular open position.

3. A ventilator comprising a rectangular frame, an inner peripheral rim within the frame, plates secured within the frame and provided with non-registering louvers, a
15 door formed in two parts, the edges of which are adapted to enclose said rim when the door is in its closed position, means for raising the said door and forcing the two parts in angular relation to each other and
20 for sustaining the door in its open position.

4. A ventilator comprising a metal frame having a ventilating plate therein, said plate provided with a series of louvers, a
25 hinged door formed of two shutters, the said shutters being hingedly secured to one another, and their adjacent edges overlapping, a shaft for raising the shutters to force them in angular relation to each other, and means cooperating with said shaft
30 forming a two-legged support for holding the plates in their angular position.

5. A ventilator comprising an integral frame, said frame provided with an inner peripheral rim, plates provided with louvers
35 secured within the frame and the louvers being positioned one above the other when the plates are in their assembled position, a cover box-like in cross section, pivoted to the frame and cooperating with the inner
40 peripheral flange when the cover is in its closed position, said cover formed of two sections pivoted at their adjacent edges, an operating shaft secured to the lower section and means cooperating with the frame
45 and with the operating shaft to hold the cover in its opened position.

6. A ventilator comprising a frame, a shutter formed in two sections pivoted to the upper portion of the frame, louver plates
50 within the frame, an offset operating shaft supported by the lower section of the shutter and having an arm at its one end and a shorter arm at its opposite end, the said frame provided with a slot at its one side
55 and a link at its other side, the link cooperating with the shorter arm and the longer arm operating in said slot to thereby hold the shutter in its open position when said operating shaft is in one position and holding the shutter closed when the shaft is in its other position.

7. A ventilator comprising a frame, louver plates within the frame, a closure for the said louver plates comprising a sectional
65 door, an operating shaft secured to the

lower section of the door, a pivoted link at one side of the frame, the frame at its opposite side provided with a slot, said operating shaft cooperating at its one end with the link and having an arm movable in the
70 slot at the other end to thereby hold the sectional door in either its open and closed positions, depending on the position of the operating shaft.

8. A ventilator comprising a frame having louver plates secured therein, a shutter formed of two sections pivotally hung to said frame, said frame provided with a link near its lower portion and a slot at its opposite side, an operating shaft carried by
75 the lower section and having an arm at one end extending within said slot to form a pivotal point directly opposite the pivotal point of the link, said shaft being offset near its opposite ends to thereby form a support
80 when the sections of the shutters are swung upwardly and outwardly from its hung position.

9. A ventilator comprising a frame, ventilating means secured within the frame, a sectional shutter pivoted to the upper portion of the frame, the upper section adapted to swing upwardly and outwardly, and the lower section adapted to pivot about two points, means secured to the lower section
90 to form an angular support to thereby hold the shutter in its open position, and to also hold the shutter in its closed position.
95

10. A ventilator comprising a frame, louver plates secured within the frame, a link
100 pivoted to one side of the frame, said frame provided with a slot on its opposite side, a sectional shutter hingedly connected at its top to the frame, an offset operating shaft carried by the lower section and having an integral arm extending into the said slot, the opposite end of said operating shaft fitting within said link so that the rotation of
105 said operating shaft will force the arm downwardly in said slot and said link outwardly to thereby hold the shutter in its open position.
110

11. A ventilator comprising a cast metal frame, louver plates within the frame, a shutter pivoted to the frame, formed of two sections, operating means for opening and closing the shutters carried by the lower section, said operating means comprising an offset shaft having a vertically extending arm at one end and a horizontally
115 extending projection near its other end, one side of the frame provided with a slot and a link oppositely positioned on the opposite side of the frame so that a rotatable movement of said shaft will form angular extending supports for holding the shutter in its open position.
